UNITED STATES PATENT OFFICE.

MICHAEL THOMPSON, OF GOODRICH, KANSAS.

LARD, FRUIT, AND OIL PRESS.

SPECIFICATION forming part of Letters Patent No. 367,865, dated August 9, 1887.

Application filed February 18, 1887. Serial No. 228,106. (No model.)

To all whom it may concern:

Be it known that I, MICHAEL THOMPSON, a citizen of the United States, residing at Goodrich, in the county of Linn and State of Kansas, have invented new and useful Improvements in Lard, Fruit, and Oil Presses, of which the following is a specification, reference being had to the accompanying drawings.

This invention relates to certain improvements in portable presses for lard, oils, and similar articles, which will be hereinafter more fully described, and pointed out in the claim.

In the drawings accompanying and forming a part of this specification, Figure 1 is a transverse vertical section of the press with a drip-pan below. Fig. 2 is an under side view of the sieve. Fig. 3 is a transverse vertical section of Fig. 2. Fig. 4 is a plan view of the removable spider, which is shown in its proper place in Fig. 1. Fig. 5 is a perspective view of a block which is placed between the lever and the follower.

A represents a cylindrical vessel, having a funnel-shaped bottom, A', in which bottom is a convenient-sized opening, a. This opening a has a flanged rim or spout, a', extending a short distance below the bottom, and on it is a removable rim or ring, b, which has on its lower edge a fine wire sieve, b'. The cylinder 25 A is supported on legs B B, &c., at a convenient distance above the ground or table, so that a drip-pan, C, can be placed under it to catch the drippings from the press.

D is a spider, which rests loosely upon the bottom of the cylinder A, and has slots d d, &c., all around it to permit the oil or other liquid matter to pass into the funnel A' and to the drip-pan C.

E is a lever, which is pivoted at one end by 30 a pin, f', to projecting standards F, fastened

at the top of the cylinder A on one side. At the opposite side of the cylinder are two other standards, F', with holes f in them, so that when the lever E is brought down, as shown in Fig. 1, a pin, f'', can be inserted above the lever to keep it down.

In Fig. 5 is shown a perspective view of a small block, e, two of which are seen in section in Fig. 1 under the middle of the lever and above the follower G, any number of which 50 can be used as the compression in the press takes place.

G is a follower-plate, which is placed above the material to be compressed, and on which, by means of the blocks e e, &c., the lever operates upon the follower. A bail-wire, H, is attached to the cylinder A by the ears h, by which the press can be easily transported from place to place. The whole may be economically constructed of cast metal of such thickness as will sustain the pressure required to express the oil or other liquid from the coarse material to be operated upon, which latter is held upon the spider D, made removable for the purpose of cleansing.

What I claim is—

A portable press for lard, fruit, oil, &c., comprising the cylinder A, terminating in a funnel-shaped bottom, A', and the orifice a, covered by removable sieve b, the removable 70 spider D, the follower G, lever E, blocks e e, bail-wire H, and standards F F', all substantially as and for the purpose described.

In testimony that I claim the foregoing as my own I hereto affix my signature in presence 75 of two witnesses.

MICHAEL THOMPSON.
